[57] ABSTRACT

A drain opener composition and process comprising the application of an aqueous solution of a soluble metallic hydroxide, a chlorine releasing salt, and a catalyst to the clogged drain for fast opening of said drain.

4 Claims, No Drawings

DRAIN OPENER

BACKGROUND OF THE INVENTION

1. Field of the Invention

This invention relates to a drain opener and more particularly to a drain opener of the soluble metal hydroxide type.

2. Description of the Prior Art

Heretofore, drain openers consisted of four basic types: (1) inhibited sulfuric acid; (2) sodium or potassium hydroxide solutions; (3) sodium or potassium hydroxide with available chlorine such as sodium or calcium hypochlorite; and (4) sodium or potassium hydroxide pellets or flakes with flaked, chipped or powdered aluminum.

The sulfuric acid type was considered the best from the standpoint of overall efficiency. It had the ability to react with most types of organic obstructions quickly. However, its major disadvantage was its great danger of causing permanent injury if not properly used.

The sodium or potassium hydroxide types, whether liquid or dry, (No. 2, above), or when mixed with aluminum (No. 4, above), were effective against grease and greasy soil type clogs but had little effectiveness towards hair, paper, or fabric, quite often found in clogged systems.

The alkali-hypochlorite salt type (No. 3, above), degraded fibrous materials. Unfortunately, the chlorination and subsequent degradation was very slow, requiring a number of hours for dissolution to take place.

SUMMARY OF THE INVENTION

Objectives

An object of this invention is to provide a unique drain opener composition.

Another object is to provide a drain opener composition of fast action.

Still another object is to provide a drain opener composition which is safe.

A further object is to provide a drain opener composition which is economical.

A still further object is to provide a drain opener composition which is effective against grease, as well as hair, paper and fabric.

Other objects of the invention will in part be obvious and will in part appear hereinafter.

BROAD DESCRIPTION OF THE INVENTION

In accord with the above objectives, a unique composition for drain opening has now been found. It comprises 10-60% by weight of a soluble metallic hydroxide, 0.1-15.0% by weight of a chlorine releasing salt, and 0.01-10.0% by weight of a catalyst selected from the metallic chlorides of the period six metals of the periodic table of the elements, such as, for example, barium, cesium, platinum, gold.

The invention accordingly comprises the several steps and the relation of one or more of such steps with respect to each of the others, and the composition possessing the features, properties and the relation of components which are exemplified in the following detailed disclosure and the scope of the invention will be indicated in the claims.

DETAILED DESCRIPTION OF THE PREFERRED EMBODIMENTS

For a fuller understanding of the nature and objects of this invention, reference should be had to the following detailed examples:

EXAMPLE I

The following ingredients are admixed to form a drain opening solution:

	% by weight
Potassium hydroxide (45% Aq. Sol.)	50.00
Trichloroisocyanuric acid	1.00
Barium Chloride	0.05
Water	48.95
	100.00

The potassium hydroxide is the soluble metallic alkali, the trichloroisocyanuric acid is the chlorine releasing salt and the barium chloride is the catalyst.

EXAMPLE II

The following ingredients are admixed to form another drain opening solution:

	% by weight
Potassium hydroxide (45% aq. sol.)	50.00
Calcium hypochlorite	1.00
Barium chloride	0.05
Water	48.95
	100.00

In the above Example, calcium hypochlorite is the chlorine releasing salt.

TEST PROCEDURES

When tests are run using the compositions of Examples I and II as compared to a non-chlorinated drain opener, and a chlorinated non-catalyzed drain opener, the quickness of the action is observed. When the test is run under equal conditions by suspending 0.5 gm. of human hair in 50 ml. of distilled water and adding 50 ml. of each test product respectively, the time for complete dissolution of the hair was noted as follows:

	Product	Dissolution Time
50	Of Example I	6 minutes
	Of Example II	14 minutes
	Non-chlorinated drain opener	No effect, after 8 hours (liquid Draino)
	Chlorinated, no catalyst drain opener	1 hour (liquid PlumR)

55 It should be evident from the above that the catalyst provides, in one instance, a ten-fold increase, and in the second instance, a four-fold increase in time to open. Thus a substantial improvement has been shown.

EXAMPLE III

The following ingredients were admixed:

	% by weight	
65	Potassium Hydroxide (45% aq. sol.)	50.00
	Calcium Hypochlorite	1.00
	Barium Chloride	0.05
	Nonylphenoxypolyethylene oxyethanol	0.50
	Water	48.45

-continued

	% by weight
	100.00

	% by weight
5	Sodium Hydroxide
	40.00
	Sodium Hypochlorite
	4.00
	Gold Chloride
	0.10
	Water
	55.90
	100.00

EXAMPLE IV

The following ingredients were admixed:

Sodium Hydroxide	40.00
Trichloroisocyanuric Acid	1.00
Barium Chloride	0.10
Water	58.90
	100.00

EXAMPLE V

The following ingredients were admixed:

Sodium Hydroxide	40.00
Sodium Hypochlorite	4.50
Barium Chloride	0.05
Water	55.45
	100.00

EXAMPLE VI

The following ingredients were admixed:

	% by weight
Ammonium Hydroxide	40.00
Calcium Hypochlorite	1.00
Barium Chloride	0.05
Water	58.95
	100.00

EXAMPLE VII

The following ingredients were admixed:

Potassium Hydroxide (45% aq. sol.)	50.00
Calcium Hypochlorite	1.00
Platinum Chloride	0.05
Water	48.95
	100.00

EXAMPLE VIII

The following ingredients were admixed:

Potassium Hydroxide (45% aq. sol.)	50.00
Trichloroisocyanuric Acid	1.00
Cesium Chloride	0.05
Water	48.95
	100.00

EXAMPLE IX

The following ingredients were admixed:
